(57) **CLAIM**

The ornamental design for a toy bat, as shown and described.

DESCRIPTION

FIG. 1 is a front perspective view of a toy bat showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are for the purpose of illustrating holes in balls used with the toy bat and form no part of the claimed design.

The parallel diagonal lines shown in the head portion of the toy bat represent a transparent material.
